UNITED STATES PATENT OFFICE.

DAVID BAIN, OF PASSAIC, NEW JERSEY, ASSIGNOR TO BLAUVELT-WILEY PAPER MANUFACTURING COMPANY, OF NEW YORK, N. Y., A CORPORATION OF NEW JERSEY.

MACHINE FOR WINDING FABRICS.

1,073,946.

Specification of Letters Patent. Patented Sept. 23, 1913.

Application filed April 17, 1912. Serial No. 691,401.

To all whom it may concern:

Be it known that I, DAVID BAIN, a citizen of the United States, residing at Passaic, in the county of Passaic and State of New Jersey, have invented certain new and useful Improvements in Machines for Winding Fabrics, of which the following is such a full, clear, and exact description as will enable any one skilled in the art to which it applies to make and use the same, reference being had to the accompanying drawings, forming a part of this specification.

My invention relates to machines having a collapsible support for the board around which the fabric is wound in the form of a bolt, and the principal objects of my present improvements are to provide such a machine to facilitate the ease with which the bolt with its contained board may be removed and to prevent the fabric from being slack on the board when the bolt is removed.

With these and other objects in view my invention consists in the novel and peculiar arrangements and combinations of the several different parts of the device, all as hereinafter fully set forth and then pointed out in the claims.

I have illustrated a type of my invention in the accompanying drawings, wherein:—

Figure 1 is a side view of a cloth winding machine provided with my improvements with the parts in winding position. Fig. 2 is a similar view to Fig. 1 with the board support detached at one end and collapsed in position for the removal of the bolt and its board. Fig. 3 is an enlarged broadside view of the board support in winding position, and with the heads to which the support is attached shown in section. Fig. 4 is an enlarged cross-sectional view with several turns of the fabric around the board and the support, the support being shown in winding position. Fig. 5 is a similar view to Fig. 4, with the board support in collapsed position. Fig. 6 is an enlarged vertical sectional view, the plan of the section being indicated by line 6—6, in Fig. 3. Fig. 7 is a detailed view, showing the pivoted ends of the arms of the support and the head to which the arms are attached, the head being shown in vertical section and the two arms being in collapsed position.

Referring to the drawings, in which like numbers of reference designate like parts

throughout, 1 is a suitable frame having upon the outer sides thereof brackets 2 and 3 respectively. Mounted in opposite sides of the frame and the brackets are two axially aligned journals 4 and 5, the former being longitudinally adjustable toward and away from the other journal. The adjustable journal 4 is mounted in a revoluble sleeve 6, which is mounted in suitable bearings in the frame and the bracket 2. In the outer end of the sleeve 6 is mounted a longitudinally adjustable screw shaft 7 having a hand wheel 8 for turning it and this shaft is swiveled at 9 to the end of the journal 4, which is connected with the sleeve by a spline 10, which permits the journal to be rotated by the sleeve and at the same time to be adjusted axially within the sleeve. On the sleeve 6 is secured a gear wheel 11 which rotates the sleeve and is in turn driven by a pinion 12 secured upon the drive shaft 13 which is operated by a pulley 14 and a belt 15. Upon the other end of the drive shaft 13 is fixed a pinion 14^a, similar to the pinion 12, and which in turn drives a gear wheel 16 fixed upon the journal 5 and which serves to drive the journal in unison with the opposite journal 4. Clutches 17 are arranged in operative connection with the drive shaft 13 to throw the pinions 12 and 14 into and out of engagement with their respective gears.

A T-shaped head 18 is secured to the journal 5 and is formed with a recess 19 in its elongated part and within this recess are pivoted at 20 and 21 respectively the lugs 22 and 23 on the ends of the arms 24 and 25 which form the support for the cloth board. These arms 24 and 25 are arranged in parallelism and in the same plane with their other ends detachably secured to a head 26 secured to the adjustable journal 4. The head 26 is formed with a recess or groove 27 extending across the length thereof, and with cavities 28 and 29 formed in the bottom of the groove. At the central point of the bottom of the groove 27 is a V-shaped projection 30 with the tapering end thereof pointing upwardly from the bottom of the groove. The free ends of the arms 24 and 25 are provided with lugs 31 and 32 respectively. These lugs are adapted to enter the cavities 28 and 29 respectively in the bottom of the groove, when the head 26 is moved inwardly by 110

the adjustment of the journal 4. At the same time the sides of the groove 27 receive and clamp the adjacent edges of the arms 24 and 25, as shown in Fig. 3. This 5 makes a firm coupling between these parts when the two arms are arranged in winding position and the journal is rotated. The arms 24 and 25 are readily detached from the head 26 by turning the hand wheel 8 so 10 as to withdraw the screw 7 and the connected journal 4. In this longitudinal movement of the journal 4 the lugs 31 and 32 are gradually freed from the cavities in the head and then they may be lowered into the 15 inclined position as shown in Fig. 2. When the bolt of cloth with its board is to be removed from the supporting arms 24 and 25, the free ends of the arms are detached from the head 26 as described. In order to prevent 20 the too sudden dropping of the free ends of the arms, the tapering projection 30 is provided for receiving the lug 32 on the end of the upper arm which may gradually slide off of such projection and permit the 25 easy descent of the arms with the bolt of cloth thereon.

It will be noted that the supporting arms 24 and 25, taper in cross section from their inner edges outwardly to the outer edge 30 where it is much thinner than at the inner edge. In winding a bolt of cloth on the board 33 which is usually a paper board, the board is placed flatly against the sides of the arms after the same have been placed 35 in winding position as shown in Figs. 1, 3 and 4. The board is considerably wider than the aggregate width of the two arms, even when the arms are spaced in their winding position. The board is held 40 against the arms and the fabric 34 which is led from a roll 35 is passed around the board and its supporting arms and drawn taut, whereupon the machine is started and the winding of the bolt 36 is effected. The 45 tension on the fabric being exerted against the opposite long edges of the board acts to warp it likewise the swelled or thickened central portion of the two winding arms, as will be understood more particularly in 50 Figs. 4 and 5. When the winding of the bolt is completed, the journal 4 is drawn outwardly so as to release from the head 26 the lugs 31 and 32 on the ends of the two supporting arms. When so released the 55 two arms with the bolt and board are gradually dropped down into the position shown in Figs. 2 and 7 and this movement brings the two adjacent edges of the supporting arms together and reduces to that extent 60 the aggregate width of the two arms, and as the thickened inner edges of the arms are brought together, the amount of space occupied by the arms when spaced being reduced, the arms are not held so tightly in 65 the bolt which together with the board may

be drawn off endwise. As the bolt leaves the arms, the board springs into straight position and thereby takes up any slack which there may be in consequence of the absence of the two arms. In this way, I 70 obtain a firmly wound bolt of fabric without any slack in the same. After the bolt has been stripped from the arms in their released position, the arms are raised into horizontal position and again attached to 75 the head 26, whereupon another board being applied to the arms, another bolt may be wound thereon.

I wish to be understood as not limiting my invention to the particular construction 80 of the various different parts of the same, as it is evident that modifications may be made in such parts without, however, departing from the spirit of my invention.

Having thus described my invention, what 85 I claim and desire to secure by Letters Patent is;

1. In a machine for winding fabric around a board, the combination of a revoluble support against which the cloth-board is placed sidewise and means for rotating the said support, the said support having the part at its axis of rotation thicker than the outer edges thereof for engaging and serving to warp or bend the 95 cloth-board when the latter is pressed against the support by the tension of the cloth during the winding and resumes its normal condition when removed from said support, substantially as described. 100

2. In a machine for winding fabric around a board, the combination of a revoluble support against which the cloth-board is placed sidewise and means for rotating the said support, the said support consisting in a pair of suitably spaced parallel pivoted arms having the part at its inner edge thicker than the outer edge for engaging the cloth-board and acting to warp it when pressed against said arms, whereby 110 the cloth-board is bent or warped during the winding and resumes its normal condition when removed from said supporting arms, substantially as described. 105

3. In a machine for winding fabric 115 around a board, the combination of a rotatable support against which the cloth board is placed and means for rotating the said support, the said support consisting in a pair of suitably spaced parallel arms pivoted at one end, a pair of axially-aligned journals having means for driving them and one of them being capable of longitudinal adjustment, a head carried on the inner end of each of said journals, the said pair 120 of arms being each pivoted at one end to the head on said non-adjustable journal and adapted to be releasably attached to the head on said adjustable journal, the free ends of said arms being provided with lugs 125 130

and the head on said adjustable journal being provided with sockets for receiving said lugs on the arms to lock the arms to the head and said head being provided with a 5 V-shaped projection between said sockets, substantially as described.

4. In a machine for winding fabric around a board, the combination of a rotatable support against which the cloth board 10 is placed and means for rotating the said support, the said support consisting in a pair of suitably spaced parallel arms pivoted at one end, a pair of axially-aligned journals having means for driving them 15 and one of them being capable of longitudinal adjustment, a head carried on the inner end of each of said journals, the said pair of arms being each pivoted at one end

to the head on said non-adjustable journal and adapted to be releasably attached to the 20 head on said adjustable journal, the free ends of said arms being provided with lugs, the said head on said adjustable journal having its outer face grooved for receiving the ends of said arms, and sockets formed 25 in the bottom of said groove for receiving said lugs on the arms, substantially as described.

In testimony whereof, I have hereunto set my hand in the presence of the two 30 sub-scribing witnesses.

DAVID BAIN.
